UNITED STATES PATENT OFFICE.

JAMES MCADAM, OF POSTVILLE, IOWA.

BUTTER-TUB.

SPECIFICATION forming part of Letters Patent No. 357,936, dated February 15, 1887.

Application filed November 15, 1886. Serial No. 218,962. (No model.)

To all whom it may concern:

Be it known that I, JAMES MCADAM, a citizen of the United States, residing at Postville, Allamakee county, and State of Iowa, have 5 made certain new and useful Improvements in Butter-Tubs, of which the following is a specification.

In the drawings, Figure 1 is a perspective view of my improved butter-tub; Fig. 2, a 10 vertical section, and Fig. 3 a perspective view, of a portion of the tub, enlarged to more clearly illustrate the fastening.

A is the butter-tub; B, the cover; C, a wooden piece to strengthen and re-enforce the 15 cover; D, the fastener for the cover, and E a pivoted portion of such fastener by which it is tightened or loosened.

In making my improved butter-tub, which is intended to be an improvement on that described and shown in Letters Patent of the 20 United States, No. 309,969, issued to me December 30, 1884, and on the butter-tub described and shown in application Serial No. 205,276, filed by me June 15, 1886, which has been allowed but not yet issued, I make the butter-tub with a cover depressed as shown in those 25 patents and as shown in the drawings herein; but as the fastening device shown and described in my other patents, although practical and useful, does not wholly satisfy the demands of customers, I have adopted the form shown in my drawings herein.

Instead of employing a tongue that passes up through a slot in an outwardly-extending 35 flange, I make a hook or clasp, D, adapted to fit down upon and securely clasp the rim of the tub-top. The lower end of this hook is extended and pivoted to a piece, E, which piece is in turn pivoted at some distance from 40 its end to the side of the butter-tub. As it is turned so that the end pivoted to the extended portion of the hook D is raised or lowered, it will of course correspondingly raise or lower the hook. If the piece E be pivoted to the 45 side of the tub at a proper distance from the top, its end pivoted to the hook D will draw

it down firmly and securely upon the rim of the cover, so as to hold it in place at the time the upper end is brought between the piece D and the side of the tub. The course of the 50 piece E when being thus turned into place is shown by dotted lines in Fig. 3. Thus when the top is brought firmly and tightly into position on the tub, the lever portion of the piece E is turned in directly between the piece 55 D and the side of the tub, so as to be out of all danger of being struck and thrown out of position in handling or shipping the tubs, and all danger of accidentally loosening the top of the tub is thus avoided. The essential 60 idea contained in this method of fastening is the employment of a piece pivoted to the tub, which, as it is turned in one direction, will bear the fastening or clasping piece down firmly against the top of the tub, so as to bring it and 65 hold it in place, and as turned in the other direction will either raise the fastening-piece itself or permit it to be raised by hand. I say "permit it to be raised" because it is obvious that the piece which exerts the leverage or 70 bearing power, and by which the fastener is brought down, need not be actually pivoted to that piece, but simply bear against a shoulder or other projection thereon. I have made them without actually pivoting the two pieces 75 together; but I prefer the form which I have described above and illustrated in the drawings, and simply make this explanation in order that I may not be unnecessarily limited to the strict details of the form shown. 80

What I regard as new, and desire to secure by Letters Patent, is—

The combination, with a tub having a lid or cover, of a fastening-hook and a pivoted piece or lever drawing such hook into position 85 to hold the lid in place when turned in under the hook and freeing it when turned out from under the hook, substantially as described.

JAMES MCADAM.
